UNITED STATES PATENT OFFICE

2,480,245

ASH RECEIVER AND SNUFFER

Ward M. Irvin, Battle Creek, Mich.

Application October 18, 1945, Serial No. 622,979

4 Claims. (Cl. 131—235)

1

This invention relates to improvements in ash receivers and snuffers.

The main objects of this invention are:

First, to provide a combined ash receiver and snuffer in which cigarettes are effectively snuffed thereby avoiding the objectionable odors resulting from smoldering of the cigarette butts.

Second, to provide an ash receiver and snuffer which is of large capacity and one in which the snuffer does not become clogged until the receiver is substantially filled.

Third, to provide a structure of this character which is also adapted to receive cigar butts or stubs.

Objects relating to details and economies of the invention will appear from the description to follow. The invention is defined and pointed out in the claims.

A preferred embodiment of the invention is illustrated in the accompanying drawing, in which:

Fig. 1 is a perspective view of the ash receiver and snuffer of my invention.

Fig. 2 is an enlarged longitudinal section on line 2—2 of Fig. 3, cigarette butts being indicated by dotted lines in one of the snuffer chambers and also as discharged therefrom, a cigarette butt also being illustrated as it is introduced into the ash receiver.

Fig. 3 is a fragmentary transverse section on line 3—3 of Fig. 2.

In the embodiment of my invention illustrated, the receptacle or container designated generally by the numerical 1 is formed of molded plastic, the side walls 2, 2, end walls 3, 3, and the top 4 being formed integrally.

The bottom 5 is also desirably formed of molded plastic and has an upwardly facing groove 6 adapted to receive the bottom edges of the side and end walls. The bottom is provided with a hinge ear 7 at the outer side of one end wall, the side wall having a coacting hinge ear 8, the ears receiving the pivot or pintle 9. A spring latch 10 is secured to the upper side of the bottom to yieldably engage the keeper 11 on the inner side of the end wall remote from the hinge.

The top 4 is of considerable thickness and has inclined end portions 12. The top is provided with diagonally opposed rectangular ash receiving openings 13 of substantial size and has groove-like diagonally opposed cigarette holders 14, the inner ends of which open to the ash receiving openings 13 so that cigarettes placed in the holders may project over the openings 13.

The bore-like snuffer chambers 15 are dis-

2

posed in inwardly inclined relation in the top, the outer ends of these snuffer bores opening to the inclined surfaces 12 or disposed as shown in Figs. 1 and 2. For compactness, the snuffer chambers are arranged at the sides of the ash receiving openings and below the cigarette holder recesses, see Figs. 1 and 2.

Bore-like openings 16 are provided to receive cigar butts, these bore-like openings also opening into the inclined surfaces 12 and bisecting the ash receiving openings. This permits cigar butts of substantial length being introduced into the ash receptacle. The cigarette butts are indicated at 17.

15 The snuffer bores or chambers 15 are of such diameter that the cigarette butts are a sliding fit thereon or of such fit that they constitute plugs for the snuffer chambers, preventing longitudinal circulation of the air throughout after a butt has been introduced.

The snuffer chambers are of such length as to receive more than one cigarette butt as they are ordinarily discharged, the following butt serving to advance the preceding butt and ejecting the same from the chamber. Where there is more than one butt in the chamber the succeeding butt is extinguished almost instantly. The first butt is, however, extinguished very quickly.

20 To prevent clogging of the receptacle, each side wall is provided with a laterally and longitudinally inclined deflector 18 substantially spaced from the inner end of the snuffer chamber and also from the bottom of the receiver. As the butts are discharged from the snuffer chambers 25 they are deflected laterally toward the center of the receiver and also tend to slide longitudinally of the deflector so that they do not pile up to obstruct the snuffer chambers and the receiver may be well filled before it is necessary to empty 30 the same.

If it is desired to discontinue smoking a cigarette before it is desired to discard it, the lighted end may be introduced into the snuffer chamber and effectively snuffed without smoldering which 35 commonly results in an objectionable taste as well as an objectionable odor.

I have illustrated and described my invention in a highly practical embodiment thereof. I have 40 not attempted to illustrate or describe certain modifications or adaptations which I contemplate as it is believed that this disclosure will enable those skilled in the art to embody or adapt the same as may be desired.

Having thus described my invention, what I

claim as new and desire to secure by Letters Patent is:

1. A combined snuffer and ash receiver comprising integral top, side and end walls, the top wall being of substantial thickness and having outwardly and downwardly inclined end surfaces and being provided with separate rectangular ash receiving openings in diagonally opposed corners thereof and cigarette holder recesses aligned with said ash receiving openings and opening at their inner ends thereto to permit a cigarette disposed in a holder to project over the ash receiving opening aligned therewith, said top having inwardly inclined bore-like snuffer chambers in the other diagonally opposed corners thereof opening at their outer ends in said inclined end surfaces and to the interior of the receiver adjacent the side walls thereof and adjacent said ash receiver openings and extending below said cigarette holder recesses, the diameter of said snuffer chambers being such as to slidably receive cigarette butts, a cigarette butt therein constituting a plug preventing substantial circulation of air longitudinally through the snuffer chamber, and inwardly and longitudinally inclined deflectors mounted on the inner sides of the side walls of the receptacle in alignment with said snuffer chambers to deflect cigarette butts discharged from the snuffer chambers and ashes falling through said openings laterally.

2. A combined snuffer and ash receiver comprising integral top, side and end walls, the top wall being of substantial thickness and having outwardly and downwardly inclined end surfaces and being provided with separate rectangular ash receiving openings in diagonally opposed corners thereof and cigarette holder recesses each aligned with one of said ash receiving openings and opening at its inner end thereto and positioned in side by side relationship with the other of said openings to permit a cigarette disposed in a holder to project over the ash receiving opening aligned therewith, said top having inwardly inclined bore-like snuffer chambers in the other diagonally opposed corners thereof opening at their outer ends in said inclined end surfaces and to the interior of the receiver adjacent the side walls thereof and adjacent said ash receiver openings and extending below said cigarette holders, the diameter of said snuffer chambers being such as to slidably receive cigarette butts, a cigarette butt therein constituting a plug preventing substantial circulation of air longitudinally through the snuffer chamber, and inwardly and longitudinally inclined deflectors mounted on the inner sides of the side walls of the receptacle in alignment with said snuffer chambers to deflect cigarette butts discharged from the snuffer chambers and ashes falling through said openings laterally, said top also having diagonally opposed bore-like cigar receiving openings opening at their outer ends in said inclined end surfaces and aligned with the adjacent ash receiving openings and partially bisecting the same, whereby cigar butts discharged through said cigar receiving openings will fall on said deflectors to be deflected laterally thereby.

3. A combined snuffer and ash receiver comprising integral top, side and end walls, and a bottom adapted to be opened to discharge the contents, the top being of substantial thickness and having ash receiving openings in diagonally opposed corners thereof and inwardly inclined bore-like snuffer chambers in the other diagonally opposed corners thereof disposed at the sides of said ash receiving openings and opening to the interior of the receiver, and inwardly and longitudinally inclined deflectors on said side walls disposed within said receiver to deflect cigarette butts discharged from the snuffer chambers and ashes falling through said openings toward the center of the receiver, said deflectors being disposed in substantially spaced relation relative to the bottom of the receiver chamber, said top also having bore-like cigar receiving openings in the same corner as an ash receiving opening and in bisecting relation thereto, the thickness of said top wall in relation to the diameter of said snuffer chambers being such that said snuffer chambers extend a substantial portion of their length alongside of said ash receiver openings.

4. A combined snuffer and receiver having a top of substantial thickness and having an ash receiving opening through one end thereof and an inclined bore-like snuffer chamber through the other end thereof and inclined toward the ash receiving opening and opening to the interior of the receiver, and an inwardly and longitudinally inclined deflector on the side wall of the receiver disposed within said receiver to deflect cigarette butts discharged from the snuffer chamber and ashes discharged through said opening toward the center of the receiver, said deflector being disposed in substantially spaced relation relative to the bottom of the receiver chamber and the discharge end of the snuffer chamber, said top defining a cigarette holding recess disposed over said snuffer chamber and opening at its inner end to said ash receiving opening.
